SCISSORS SHARPENER

Edward C. Heard, Los Angeles, Calif., assignor to
 Heard & Sandwall Manufacturing Corporation,
 Huntington Park, Calif., a corporation of Calif-
 ornia.

Application July 22, 1946, Serial No. 685,525

4 Claims. (Cl. 76—82.2)

1.

This invention relates to a scissors sharpener. One object of the invention is to provide a manual sharpening device for scissors or shears. Another object is to provide a manual sharpener which simultaneously sharpens both shear edges of scissors.

These and other objects are attained by my invention which will be understood from the following description, reference being made to the accompanying drawings in which

Fig. 1 is a front elevational view showing my sharpener as used to sharpen scissors;

Fig. 2 is a top elevational view of my sharpener;

Fig. 3 is a side elevational view of the same;

Fig. 4 is an enlarged fragmentary cross-sectional view taken on the line 4—4 of Fig. 1;

Fig. 5 is a perspective view of one of the cutters;

Fig. 6 is a cross-sectional view taken on the line 6—6 of Fig. 3.

Referring to the drawings, my sharpener consists generally of two double cutter plates 11 and 12 arranged to be placed in face to face relation and to turn relative to each other, one plate 11 being attached to a handle 13 by means of which the device is reciprocated between the blades B and B¹ of scissors, S as shown particularly in Fig. 1, the cutter edges of the respective plates sliding along the shear edges of the scissor blades.

The cutter plates 11 and 12 are made of small plates of steel or other suitable metal, with a mounting hole spaced below the cutter edges and are provided on one plate edge with two integrally formed or inserted hardened metal cutters 14a and 14b, the cutting edges of which are at opposite ends of a relieved portion 16, and being arranged so that in sliding the device back and forth only one cutting edge (of each cutter plate) is in cutting contact with the shear edge of a scissor blade in one direction of sliding, and the opposite cutting edge is in cutting contact when the device is moved along the scissor blade in the other direction. The cutting edges are angularly disposed to the cutter plate surfaces, the angle corresponding to the angle of the shear edge of the scissor blades, this angle being designated A in the drawings (Fig. 4) and being usually about ten degrees. The top surfaces of the cutters 14a and 14b are also preferably relieved back of the cutting edges.

The cutter plate 11 is non-rotatably attached to the handle 13, and the cutter plate 12 is rotatably attached, by a headed screw 17, which is threaded to engage the threaded hole in the

2.

turned down end 18 of the handle 13, and also the threaded hole in the cutter plate 11, the non-threaded hole in cutter plate 12 permitting turning of the plate 12 relative to the plate 11, the head 19 of the screw 17 holding it in place. It is necessary that the adjoining surfaces of the cutter plates be smoothly fitted together so that the cutters will sharpen the cutting edges of the blades of the scissors. The juxtaposed flat surfaces of the cutter plates act as guides for sliding the device back and forth, being in contact with the inside flat surfaces of the scissor blades. Either one or both cutter plates may be free to rotate on pivot, although the sharpening is better controlled if one plate is fixed to the handle.

In using the sharpener, as much pressure as desired may be exerted on the cutters by holding the scissors by the handles in the usual operative position for scissors. The sharpener, with one double cutter in contact with each of the blades B and B¹, is reciprocated along the shear edge of the scissor blades. The relieved portion 16 and the slight surface relief on the top of the cutters permits the cutter edges to follow the curve of the scissor blades. The use of the two cutters on each cutter plate, one for sharpening the scissor blade in one direction of movement and the other for sharpening in the opposite direction of movement not only allows the sharpening of the blades throughout the effective shear length, but also gives a smoother non-jagged sharpening of the shearing edges of the scissors.

I claim:

1. A manual sharpener for scissors comprising a handle, and a pair of cutter plates, the first of said plates being non-rotatably attached to said handle and the second of said plates being pivoted in face to face relation to said first plate, each of said cutter plates consisting of two cutter edges arranged in opposed cutting position on an edge of each of said plates near opposite ends thereof, whereby one cutting edge cuts the shearing edge when the device is slidably moved along the shearing edge of a scissor's blade, the space between the two cutting edges being relieved to a depth sufficient to accommodate a curved shearing edge.

2. A manual sharpener for scissors comprising a handle, a pair of cutter plates, the first of said plates being non-rotatably attached to said handle and the second of said plates being pivoted to said first plate for relative rotary movement in face to face relation, each of said plates having two hardened cutting edges arranged on one

edge of said plate at substantially right angles thereto and spaced apart, with a relieved portion therebetween of sufficient length to accommodate a curved scissors' blade, the said cutting edge of each plate nearest the scissors pivot being adapted to sharpen a blade of the scissors on sliding it along the scissors shear edge in one direction, and the said cutting edge of each plate farthest from the scissors pivot being adapted to sharpen the same shear edge on sliding the sharpener in the opposite direction, the angular positions of the said cutting edges of the sharpener conforming substantially to the angular position of the shear edges of the scissors.

3. In a scissors sharpener adapted to be reciprocated along a scissors' blade, a cutter plate having two opposed cutting edges disposed apart and at right angles to the path of reciprocation of said cutter relative to said blade with a relieved portion in said plate between said edges, said opposed cutting edges being spaced far enough apart to maintain the cutting edge in cutting relation to the blade when said blade has a slight curvature.

4. A scissors sharpener comprising a pair of sharpening members each having two cutting edges, said members being adapted to simulta-

neously sharpen the shearing edges of both scissors blades and being pivoted together so that the said cutting edges are guided along the shearing edges of the blades by the adjacent non-cutting faces of one of said members, said cutting edges being disposed across said blade and spaced far enough apart to maintain the cutting edge in cutting relation when said blade has a slight curvature, said cutting edges being in opposed relation and tilted to conform to substantially the original bevel on said blade.
